DESIGN FOR A BRASSIÈRE VEST

Sara Stein, Brooklyn, N. Y.

Application April 2, 1936, Serial No. 61,910

Term of patent 14 years

To all whom it may concern:

Be it known that I, Sara Stein, a citizen of the United States, and resident of New York city, (Borough of Brooklyn), in the county of Kings and State of New York, have invented a new, original, and ornamental Design for a Brassière Vest, of which the following is a specification, reference being had to the accompanying drawing, forming a part thereof, and of which Figure 1 is a view in front elevation, Fig. 2 is a view in side elevation, Fig. 3 is a view in rear elevation, and Fig. 4 is a front view in flat open position with parts removed, of a brassière vest showing my new design.

I claim:

The ornamental design for a brassière vest substantially as shown.

SARA STEIN.
